UNITED STATES PATENT OFFICE.

ELMER KEEBLER, OF CHICAGO, ILLINOIS, ASSIGNOR TO THE MECHANICAL MANUFACTURING COMPANY, OF CHICAGO, ILLINOIS, A CORPORATION OF ILLINOIS.

BUMPING-POST FOR FREIGHT-CARS.

1,348,223.

Specification of Letters Patent. Patented Aug. 3, 1920.

Application filed November 14, 1919. Serial No. 337,963.

To all whom it may concern:

Be it known that I, ELMER KEEBLER, a citizen of the United States, residing at Chicago, in the county of Cook and State 5 of Illinois, have invented certain new and useful Improvements in Bumping-Posts for Freight-Cars, of which the following is a specification.

This invention relates to new and useful 10 improvements in bumping posts for freight cars and the like.

An important object of the invention is to provide a bumping post wherein the sheering tendency usually present in such 15 devices is eliminated.

A further object is to provide a bumping post wherein the bumping stress is directed against the ties of the track.

Other objects and advantages will be apparent throughout the course of the following description.

Referring to the drawings wherein for the purpose of illustration is shown a preferred embodiment of my invention and wherein 25 like reference characters designate like parts throughout,

Figure 1 is a plan view of my bumping post.

Fig. 2 is a side elevation thereof.

Fig. 3 is a section taken on the line 3—3 of Fig. 2.

Fig. 4 is a section taken on the line 4—4 of Fig. 2, and

Fig. 5 is a section taken on the line 5—5 of Fig. 2.

Referring now more particularly to the drawings, the numeral 10 indicates a bumping member proper, provided forwardly with a bumping face 11.

40 The bumping member 10 has portions which taper rearwardly and these portions are provided with an irregular surface 12, adapted to coat with one side of rails 13. The irregular surface 12 provides an under 45 cut portion 14 which receives the flange 15 of the rail 13. Bolts 16 extend through the bumping member 10 and rails 13 holding them in an assembled position.

The rails 13 diverge forwardly and 50 downwardly and terminate in parallel portions 17 spaced apart at a less distance than the rails T of the track proper, and between the rails T and the parallel portions 17 of the rails 13, are interposed spacing members 18. It will be seen by inspecting Fig.

3, that these spacing members 18 engage under the heads of the rails T and 13, and abut the webs and flanges thereof.

A bolt 19 extends through the rails T, spacing members 18, and rails 13, and is 60 provided with a tubular spacing member 20 intermediate the rails 13. By inspecting Fig. 1, it will be seen that this bolt 19 extends through the rails at the rear of the horizontal portion 17 or that part of the 65 horizontal portion 17 adjacent the bumping member 10. It will be apparent that in event of force being applied in a horizontal direction to the bumping face 11, the rails 13 will have a tendency to bind 70 downwardly upon the arc taken from the bolt 19, such arc being indicated upon Fig. 1. Short bolts 21 are also provided which extend through the spacing member 18 and portions 17 of the rails 13 and the rails T, 75 and the portions 17 are secured to the ties 22 by means of spikes 23.

The bumping member 10 is provided with rearwardly and downwardly extending portions 24 which are reduced as at 25 to fit 80 within the channels of channel iron supports 26. The upper ends of the reduced portions 25 terminate in shoulders 27 which engage the upper end of the channel iron supports 26. The supports 26 are secured 85 to the portions 24 by means of bolts 29 or the like. It will be apparent that sheering stress is not applied to the bolts 29, because of the fact that the shoulders 27 of the portions 24 engage the upper end of the supports 26 solidly.

The lower end of each support 26 is shaped as at 30 to conform to the shape of the flange F of the rail T. A through bolt 31 extends through the supporting members 26 and the web of the rail T. At each end this bolt is provided with a pair of bevel washers 32 and 33, the washer 32 being disposed interiorly of the support 26 and the washer 33 being disposed intermediate the support 26 and the web of the rail T. The supports 26, rail T, and washers 32 and 33 are firmly clamped together by means of nuts 34 and 35, disposed upon the bolt 31.

100 As previously stated, pressure against the face 11 of the bumping member 10 causes a tendency of the member 10 to move on the arc indicated on Fig. 2. It will be noted 105 that the arc upon which the member 10 has 110

a tendency to move, intersects the bases or lower ends of the supports 26 at a point approximately centrally thereof. It will thus be obvious that the entire force or practically the entire force of the blow will be exerted downwardly upon the supports 26 and as these supports have a firm engagement with the flanges of the rails T, the force is transmitted to these flanges and subsequently to the ties and the road bed. The lower ends of the supports 26 may be secured to the webs of the rails T by as many bolts as is deemed advisable. In the present instance, I have shown two extra openings 36 for the reception of short bolts to connect the supports 26 and the webs of the rails T.

As many changes in the shape, size, and arrangement of the various parts shown may be made, I do not limit myself to the specific structure herein shown and described, but may make any such changes without departing from the spirit of the invention or the scope of the subjoined claims.

25 What I claim is:

1. In a bumping post for freight cars and the like adapted for insertion intermediate the rails of the track, a bumping element embodying a pair of downwardly and rearwardly extending portions, a pair of angularly disposed supports having their lower ends shaped to conform to the shape of the flanges of the track rails and secured thereto and their upper ends secured to said downwardly extending portions, downwardly and forwardly extending braces secured to said bumping element and said track rails the point of contact of said supports with said flanges being on an arc having as its center the point of connection of said braces to said track rails and passing through said bumping element.

2. In a bumping post for freight cars and the like, adapted for insertion intermediate the rails of the track, a bumping element embodying a pair of downwardly extending portions, a pair of angularly disposed supports having their lower ends shaped to conform to the shape of the flanges of the track rails and secured thereto and their upper ends secured to said downwardly extending portions, said downwardly extending portions being provided with shoulders abutting the upper ends of said supports, downwardly and forwardly extending braces secured to said bumping element and said track rails the point of contact of said supports with said flanges being on an arc having as its center the point of connection of said braces to said track rails and passing through said bumping element.

3. In a bumping post for freight cars and the like adapted for insertion intermediate the rails of the track, a bumping element embodying a pair of downwardly extending

portions, a pair of angularly disposed supports having their lower ends shaped to conform to the shape of the flanges of the track rails and secured thereto and their upper ends secured to said downwardly extending portions, said downwardly extending portions being shaped to conform to the shape of said supports and providing shoulders abutting the upper ends thereof, downwardly and forwardly extending braces secured to said bumping element and said track rails the point of contact of said supports with said flanges being on an arc having as its center the point of connection of said braces to said track rails and passing through said bumping element.

4. In a bumping post for freight cars and the like adapted for insertion intermediate the rails of the track, a bumping element, a bracing member for said bumping element secured to said bumping element and to the tracks and a support for said bumping element engaging the flange of the track with its lower end and abutting the bumping element with its upper end, the point of contact of said support with said flange being on an arc having as its center the point of connection of said bracing member to said tracks and passing through said bumping element.

5. In a bumping post for freight cars and the like adapted for insertion intermediate the rails of the track, a bumping element embodying a pair of downwardly extending portions, a pair of forwardly diverging braces secured at their upper ends to said bumping post and at their lower ends to the rails of the track, and a pair of angularly disposed supports having their lower ends engaging the flanges of the rails and their upper ends abutting said downwardly extending portions and secured thereto, the point of contact of said supports with the flanges of the rails being on an arc having as its center the point of connection of said forwardly diverging braces with the rails of the track and extending through said bumping element.

6. In a bumping post for freight cars and the like adapted for insertion intermediate the rails of the track, a bumping element embodying a pair of downwardly extending portions, a pair of forwardly diverging braces secured at their upper ends to said bumping post and at their lower ends to the rails of the track, said braces being provided with flanges, undercut recesses formed in said bumping element adapted to receive the flanges, and a pair of angularly disposed supports having their lower ends engaging the flanges of the rails and their upper ends abutting said downwardly extending portions and secured thereto, the point of contact of said supports with the flanges of the rails being on an arc having as its center

the point of connection of said forwardly diverging braces with the rails of the track and extending through said bumping element.

5 7. In a bumping post, a bumping element, a rearwardly and downwardly extending support secured to said bumping element and to the tracks, a forwardly and downwardly extending brace secured to said

10 bumping element and to the tracks, the point of contact of said support with the track lying on an arc having as its center the point of connection of said brace to said tracks and passing through said bumping

15 element.

8. In a bumping post for freight cars and the like adapted for insertion intermediate the rails of the track, a bumping element embodying a pair of downwardly and rear-

20 wardly diverging portions, a pair of downwardly and rearwardly diverging supports having their lower ends shaped to conform to the shape of the flanges of the track rails and secured thereto and their upper ends

25 secured to said downwardly extending portions, said downwardly extending portions being shaped to conform to the shape of said supports and providing shoulders abutting the upper ends thereof.

30 9. In a bumping post for freight cars and the like adapted for insertion intermediate the rails of the track, a bumping element embodying a pair of rearwardly and downwardly diverging portions, a pair

35 of rearwardly and downwardly diverging channel iron supports having their lower ends shaped to conform to the shape of the flanges of the track rails and secured to said track rails and their upper ends secured

40 to said rearwardly and downwardly extending portions, the rearwardly and down-

wardly extending portions of said bumping element being provided with reduced portions conforming to the shape of and entering the channels of said channel iron 45 supports, said reduced portions terminating in shoulders abutting the upper ends of said supports.

10. In a bumping post for freight cars and the like adapted for insertion intermediate the rails of the track, a bumping element embodying a pair of downwardly and rearwardly extending portions, a pair of downwardly and rearwardly diverging

50 channel iron supports having their lower ends shaped to conform to the shape of the flanges of the track rails and their upper ends secured to said downwardly extending portions, said downwardly extending portions being provided with reduced portions 55

conforming to the shape of and entering the channels of said channel iron supports, said reduced portions terminating in shoulders abutting the upper ends of said supports, a

60 bolt extending through the webs of said track rails and said supports, washers upon said bolt intermediate said supports and said rail webs, each of said washers being pro-

vided with a vertical face engaging the web and a bevel face engaging the angular sup-

port, bevel washers upon said bolts engag-

65 ing the faces of said supports remote from said first named washers, nuts acting against said last named washers, and nuts upon the ends of said bolt and acting against the outer 70 face of said rail webs.

In testimony whereof I affix my signature in presence of a witness.

ELMER KEEBLER.

Witness:

W. P. BUCHOLZ.
